FIREPLACE

August Robert Fredlund, Santa Barbara, Calif.

Application May 14, 1938, Serial No. 208,072

8 Claims. (Cl. 126—121)

This invention relates to a fireplace.

An object of the invention is the provision of a fireplace which is made of heavy cold rolled black iron or cast iron in which a drum is mounted and tapered towards the center so that the hot gases of combustion must pass through a tortuous path before they escape from the center of the coiled drum and are directed to a central flue, the cold air being carried up over the coiled 5 drum being rapidly and economically heated before it is passed out into the room.

Another object of the invention is the provision of an all-metal fireplace which may be built into the fireplace or which may be moved into the 15 fireplace as a unit with the walls of the unit being insulated to prevent fire hazards while providing for a tortuous path of the gases of combustion from the firebox to a flue and presenting to incoming cold air a broad heating surface before 20 the air is conducted into a room.

A further object of the invention is the provision of an all-metal insulated fireplace having 25 fresh air conduits for supplying the fireplace with the proper amount of air and with a spiral flue providing an ever-decreasing coiled passage for the combustion gases before said gases are discharged into a common flue so that fresh air which will be discharged into the room will come 30 in contact with a large heating surface and over the most intensely heated portions of the coiled flue.

This invention will be best understood from a 35 consideration of the following detailed description, in view of the accompanying drawings forming a part of the specification; nevertheless, it is to be understood that the invention is not confined to the disclosure, being susceptible of such changes and modifications as define no material departure from the salient features of 40 the invention as expressed in the appended claims.

In the drawings:

Figure 1 is a vertical section of my fireplace taken along the line 1—1 of Fig. 2.

Figure 2 is a front view of the fireplace.

Figure 3 is a vertical transverse section taken along the line 3—3 of Fig. 1.

Figure 4 is a view in perspective of a metal framework forming the housing for the fireplace.

Figure 5 is a view in perspective of the insulated rear wall of the fireplace.

Figure 6 is a view in perspective of a convolute flue located within the fireplace.

Figure 7 is a fragmentary view in perspective showing one form of a decorative finish for the front of the fireplace, and

Figure 8 is a view in perspective of a protective plate at the forward end of the fireplace.

Referring more particularly to the drawings, 5 10 designates a base member below an open fireplace 11 which has a floor 12. A grate 13 is mounted above the floor at the rear of the firebox and is supported in any approved manner as by legs 14 from the floor 12.

Referring more particularly to Fig. 4, it will be seen that the housing of the fireplace consists of 10 15 metal side plates 15 and 16 which are provided with a V-shaped horizontal flange 17 that connects the upper sections 18 and 19, respectively, to the plates 15 and 16. Plates 20 and 21, respectively, are connected to the inner faces of 15 20 the plates 18 and 19. It will be noted that the plates 18 and 20 and the plates 19 and 21 are provided with smaller passages 22 for a purpose to be presently explained. The forward edges of the plates 15, 16, 18 and 19 are provided with 20 25 lugs 23 which extend laterally therefrom and are provided with openings to receive bolts connecting the finishing plates 24 to the front face of the fireplace.

The finishing plate 24, which forms a decorative 25 front for the fireplace and shown more particularly in Fig. 7, consist of a longitudinal plate 25, a top plate 26 and a vertically disposed grill 27. These plates may be cast in one piece or they may be made separately and connected 30 together. Each of these plates is provided with flutes 28 for ornamenting the surface of the same. The plates 25 extend vertically on each side of the furnace while the plate 26 and 27 extend across the top and front. The grillwork permits 35 heated air from the fireplace to pass into the room.

The rear wall of the furnace is composed of a pair of metal sheets 30 and 31 which are spaced from each other and the space between the sheets 40 is filled with insulating material 32. It will be noted that these plates have a straight vertical wall and a curved top 33 with the plate 30 at its forward end having a vertically disposed flange 34 which is secured to the decorative plate 26. 45 The plates along their side edges are provided with perforations 35 to receive bolts for connecting the plates to perforated lugs 36 which extend inwardly from the side edges of the side walls of the housing. The bottom of the sheet 30 extends 50 below the bottom of the sheet 31 and is connected at 37 to the walls of an air chamber 38. A tortuous conduit is provided for conducting the hot gases of combustion away from the open fireplace or chamber 11 and this conduit consists 55

of a sheet of metal which is formed into a vertical wall 40 spaced from the rear wall or sheet of metal 39. The wall 40 is curved inwardly, as shown at 41, and gradually curved and rolled 5 into a convolute passage to provide a tortuous passage, as indicated by the numeral 42, and this convolute passage is defined by the spiral walls 43, 44 and 45 and terminates in a central passage 46.

10 The lower end of the wall 40 is connected at 47 to one wall of the fresh air supply conduit 38. The convolute portions of this wall, which form the flue 42, are connected by means of angle irons or lugs 48 to the side walls of the housing. The 15 remaining portions of the walls of the convolute passage merely rest against lugs 50 for supporting the curved portions in position while permitting said curved portions to expand or contract during changes of temperature.

20 The lower portions of each of the curved sections 43 and 44 are provided respectively with openings 51 and 52 which are closed by sliding doors 53 and 54, respectively. These doors may be opened for the removal of soot when necessary.

25 It will be noted, more particularly in Figs. 2 and 3, that curved pipes 55 and 56 extend from the opposite sides of the central member 45 of the flue for carrying away the gases of combustion and conducting them to a chimney 57 which 30 is normally located centrally of the fireplace. A plate 58 is disposed within the centrally disposed flue 45 for causing the gases of combustion to flow in opposite directions and into the pipes 55 and 56.

35 A plate 60 is connected at 61 with the front wall 27 while the inner end of the plate is curved upwardly, as shown at 62, and terminates in close contact with the soot door 53. Angle irons 63 connect the upwardly curved portion 62 of this plate with the front wall 27, as shown at 64.

40 It will be noted from Figs. 1, 2 and 4 that a plurality of rods 65 connect the side walls together above the fire chamber and these rods are located around the front, top and rear portion of the housing. A damper 70 controls the 45 flow of air to the chamber 11 from a supply conduit 71. This damper is operated by a rod 72 which projects forwardly and terminates in a handle 73 at the front face of the fireplace.

50 Flues 75 are in communication at the upper ends with the space between the coiled portions 44 and 45 and these flues extend downwardly to outlet pipes shown at 76 (Fig. 1). These outlet pipes are controlled by dampers 77 which in turn 55 are operated by rods 78 having a handle 79 at the forward part of the fireplace. The dampers 77 are normally closed during the initial stage of heating until the convoluted drum is hot. The dampers are then opened and the normal draft 60 will draw a certain amount of the hot combustion gases back into the furnace to pass through the grate.

65 It will be noted that the flues 75 are located upon opposite sides of the fireplace and open at their lower ends adjacent the grate.

The operation of my device is as follows: Before the fire is started the damper 77 is closed and after the convolute drum has been sufficiently heated this damper is opened so that 70 exhaust gases will be carried back from the convolute drum to the firebox to insure complete combustion of the gaseous products.

The upper end of the channel, indicated by the numeral 38a, which leads from the fresh air 75 supply pipe 38 extends directly over the heated

wall 41 and over the curved portion 43 of the drum. This hot air then is discharged through the grillwork at the upper end of the firebox.

The damper 70 controls the amount of fresh air to the grate 13 at all times.

5 The products of combustion from the grate pass upwardly along the inner face of the rear wall 40 and enter the convolute channel 42 and continue through this channel until they reach the central discharge channel 46. The baffle or plate 58 causes the products of combustion to pass outwardly in opposite directions through the curved pipes 55 and 56 where they meet in a common flue or chimney 57. As has been previously explained, some of the exhaust gases are 15 carried back through the flues 75 to points beneath the grate 13.

It will be seen by this construction that an extended surface for the fresh air which is discharged into the room has been provided so that 20 a very economical operation of the fireplace is had.

While I have shown a readily removable fireplace which has its side walls and back formed of metal it will be appreciated that these walls may be formed of fire brick as a permanent part of the fireplace while the metal top and the metal panels at the front may be readily removable since they will be made in standard sizes. The convolute flue, however, which is made of metal and readily replaceable, may have any number of coils depending upon the size of the fireplace. Where the space is restricted there will be less coils and these coils will be spaced further apart to provide the necessary draft; with the greater area of the side walls the coils may be closer together and the coils will be of a greater number. The effective transverse area of the space between the coils will always be such as to create the necessary draft.

40 I claim:

1. A fireplace comprising a grate, means forming a convolute channel merging into a central passage and having its largest portion in a position of access to the products of combustion from 45 a fire on the grate, a discharge flue connected to the central passage, and means connecting a space beneath the grate to said convolute channel for bypassing some of the products of combustion from the flue for circulation through the grate.

2. A fireplace comprising a grate, a convolute flue conducting products of combustion from the 50 grate to a chimney and presenting a large surface area to fresh air, means conducting fresh air to and around the surface before said air is discharged into a room, said flue progressively decreasing in width to a central horizontal position, and means conducting products of combustion from the central portion to the chimney.

3. A fireplace comprising a grate, a convolute flue conducting products of combustion from the 55 grate to a chimney and presenting a large surface area to fresh air, means conducting fresh air to and around the surface before said air is discharged into a room, said flue terminating in a central horizontal conduit, a partition dividing the central conduit, conduits connected to the opposite ends of the central conduit and meeting in a common conduit which enters the chimney.

4. A fireplace comprising a metal housing having the front end open, a metal plate having the side edges secured to the side walls of the housing and spaced from the rear and top wall of the housing to provide a passage for fresh air to be heated, said air being discharged into a room

through the open end of the housing, the upper end of the plate being curved to provide a convolute passage for the products of combustion, a grate in the lower portion of the housing adjacent to the metal plate, and means conducting products of combustion from said housing.

5. A fireplace comprising a metal housing having the front end open, a metal plate having the side edges secured to the side walls of the housing and spaced from the rear and top wall of the housing to provide a passage for fresh air to be heated, said air being discharged into a room through the open end of the housing, the upper end of the plate being curved in convolute form 10 to provide a tortuous passage for the products of combustion, a grate in the lower portion of the housing, and means conducting the products of combustion from the central portion of the convolute form of the plate.

15. 6. A fireplace comprising a metal housing having the front end open, a metal plate having the side edges secured to the side walls of the housing and spaced from the rear and top wall of the housing to provide a passage for fresh air to be heated, said air being discharged into a room 20 through the open end of the housing, the upper end of the plate being curved to provide a convolute passage and a centrally disposed central conduit for the products of combustion the convolute passage being in communication with the lower portion of the housing, a grate in said lower portion of the housing adjacent the plate so that the products of combustion will heat the plate, and means conducting the combustion 25 products from the convolute passage.

7. A fireplace comprising a metal housing having the front end open, a metal plate having the side edges secured to the side walls of the housing and spaced from the rear and top wall of the housing to provide a passage for fresh air to be 5 heated, said air being discharged into a room through the open end of the housing, the upper end of the plate being curved to provide a convolute passage and a centrally disposed central conduit for the products of combustion, the convolute passage being in communication with the lower portion of the housing, a grate in said lower portion of the housing, adjacent the plate so that the products of combustion will heat the plate, a partition dividing the central conduit, conduits 10 connected to the ends of the central conduit and merging at the other end thereof into the chimney. 15

8. A fireplace comprising a metal housing having the front end open, a metal plate having the side edges secured to the side walls of the housing and spaced from the rear and top wall of the housing to provide a passage for fresh air to be heated, said air being discharged into a room 20 through the open end of the housing, a grate in the lower portion of the housing, the upper end of the plate being curved to provide a convolute passage for the products of combustion opening into the lower portion of the housing, a conduit 25 connected with the convolute passage at approximately the center thereof for supplying the grate with heated products of combustion. 30

AUGUST ROBERT FREDLUND. 35
